[57] CLAIM

The ornamental design for a camera, as shown and described.

DESCRIPTION

FIG. 1 is a top, front and side perspective view of a camera showing my new design;
FIG. 2 is a front elevation view thereof;
FIG. 3 is a rear elevational view thereof;
FIG. 4 is a top plan view thereof;
FIG. 5 is a bottom plan view thereof;
FIG. 6 is a side elevational view thereof from the right of FIG. 2;
FIG. 7 is a side elevational view thereof from the left of FIG. 2; and,
FIG. 8 is a view similar to FIG. 2 but showing the parts in a different position.
